UNITED STATES PATENT OFFICE.

ANTHONY VANDERVELD, OF GRAND RAPIDS, MICHIGAN, ASSIGNOR TO GRAND RAPIDS SHOW CASE COMPANY, OF GRAND RAPIDS, MICHIGAN, A CORPORATION OF MICHIGAN.

DISPLAY DEVICE.

1,157,651.

Specification of Letters Patent.

Patented Oct. 19, 1915.

Application filed February 10, 1912. Serial No. 676,700.

To all whom it may concern:

Be it known that I, ANTHONY VANDERVELD, a citizen of the United States, residing at Grand Rapids, in the county of Kent and 5 State of Michigan, have invented an Improvement in Display Devices, of which the following description, in connection with the accompanying drawings, is a specification, like letters on the drawings representing 10 ing like parts.

The invention to be hereinafter described relates to store display devices for exhibiting goods, more particularly to such devices wherein a rotatable rack is employed for 15 supporting the goods to be displayed, and it is movable to and from a position within the case, or cabinet. In devices of this general character, the rack usually comprises a plurality of parallel supporting rods on 20 which the goods are hung, as for instance, ready-made garments, and these supporting rods are liable to injure the case or cabinet, or break the glass thereof if such rack be moved from its outer toward its inner position. 25

With these facts in view, the present invention has for its aims and purposes, to provide a display device wherein, when the rack is away from its inner position, it will be caused to automatically assume a predetermined relation with the case, to the end 30 that, should the rack be moved into the case, it will not cause injury or breakage thereof.

Other purposes and advantages of the invention will hereinafter appear from the 40 following description and accompanying drawings of one form of means for carrying the invention into practical effect, it being understood that the invention is not restricted to the illustrated and described 45 details, but that in its true scope, it is definitely set forth by the claims.

In the accompanying drawings:—Figure 1 is an end view of a display device embodying one form of the present invention. 50 Fig. 2 is a detail enlarged view showing one form of means to automatically act upon the rack to cause rotative movement of the same in positioning the rack for bodily movement into the case or cabinet. Fig. 3 55 is an enlarged elevation of the rack and its

supporting devices, some of the parts being broken away.

The case or cabinet with reference to which the rack is movable to and from an inner position, is shown by Fig. 1 as comprising any usual or suitable form of inclosing structure, that illustrated preferably comprising a base 1 and glass panels 2 at the sides and back, with doors 3, likewise provided with a glass panel to close the 60 front of the case when the rack is in inner or rear position. 65

The rack for supporting the goods may be of any usual or desired form and may be so mounted with respect to the case as to 70 enable the rack to be moved to and from a position within the case, substantially as indicated by full and dotted lines in Fig. 1.

In the present form of the invention, the case or cabinet is provided with a floor 4 below which are suitable trackways 5 on which ride the rollers 6 of a rack supporting carriage. This carriage may be of any usual or desired structure, and as shown has a column 7 rising therefrom, which, at its upper 75 portion provides a bearing 8 for a rotary shaft or upright 9. The lower end of the shaft 9 is preferably reduced in diameter as at 10 and passes through the arm 11 of a bracket 12 secured by bolts 13 to suitable 80 flanges or brackets 14 mounted on or formed as part of the column 7, the construction being such that the shaft or upright 9 may freely rotate upon its supporting carriage. 85

While the details of the described structure form a convenient mechanical device for supporting and rotating a rack, it is to be understood that the invention is not restricted to these particular devices, but that the rack, as hereinafter pointed out, may 90 be otherwise conveniently supported for rotative movement.

The shaft or upright 9 extends upward through the bearing portion 8 of the column 7 and is surmounted by a collar 15 100 which may be secured to rotate with the shaft or upright 9 by any suitable means, such as the set screw 16 in Fig. 3. Projecting from the collar 15 are the spider arms 17 provided with end supporting portions 18 105 for the bars 19 which form the supporting rods or rack on which the garments or goods are hung. 110

Projecting from the collar 15 are the arms or short shafts 20, preferably carrying suit-

able rollers 21 adapted to ride upon the upper surface of an enlarged flange portion 22 formed as part of or secured to the column 7. The flange portion 22 has inclined upper surfaces 23 upon which the rollers 21 ride and by which the rack as well as the shaft or upright 9 are supported. The inclined upper surfaces 23 of the flange 22 have their upper extremities meeting at the points 24, 10 at the front and rear of the flange 22, the construction being such that if the rack be turned from the position indicated by the dotted lines in Fig. 3 and then be released, the inclines 23 will afford a gravity slide on 15 which the rollers 21 will ride and cause the rack to assume the position as indicated by full lines in Fig. 3. In other words, when the rack is in the position indicated by full lines in Fig. 3, the bars 19 are in their predetermined position to permit the rack and carriage to be moved into the case without causing injury thereto, and if, when the rack is in its outer position, it be partially turned and then released, the gravity action of the 20 rack and its connected parts, acting through the rollers 21 and the inclined surfaces 23 which constitute a cam will cause the rack to automatically turn into the predetermined position which will permit it to be bodily 25 moved into the case without danger of the rack striking or injuring the latter. The upper surface of the flange 22 is preferably also provided with roller receiving depressions 25, one at each side of the flange 22, 30 such depressions being adapted to receive the rollers 21 when the rack has been automatically rotated into the desired predetermined position as hereinbefore indicated.

While the present form of the invention 40 has been described in connection with a gravity acting means for automatically rotating the rack into the desired predetermined position such that it will not injure the case when moved bodily into the case, 45 it is to be understood that it is not necessarily restricted thereto, but that applicant believes himself the first to provide any means which will automatically cause the rack to be rotated to a predetermined position 50 when the rack being away from inner position, it is partially turned and then freed from the hand of the operator, so that the rack may be then moved bodily into the case, without injury to the latter. When the rack 55 is thus automatically turned to the desired predetermined position for the purposes noted, it is desirable that it be locked from further rotative movement as it is moved into the case or cabinet; and as one form 60 of means to this end, applicant has provided devices which, when the rack has thus been automatically rotated to the predetermined position and is pushed toward its inner position, will so act as to cause the rack to 65 be locked from rotative movement. To

these ends, the lower portion 26 of the shaft or upright 9 is provided with two diametrically disposed lock-openings 27, Fig. 3, either of which is adapted to be engaged by the hooked upper end 28 of a lock lever 29 pivoted at 30 to a lug 31 projecting upward from the bracket or cross-bar 32. A spring 33 having one end connected to the lock lever 29 and the other to the bracket 12, serves normally to cause such engagement when the rack is rotated to its predetermined position as before explained and lever 29 is free to move.

From the construction described, it will be noted that when the upper end 28 of the lock lever 29 engages one of the recesses 27 in the shaft or upright 9, the latter is prevented from rising, the result being that the rack is prevented from rotative movement because the rollers 21 secured to the rack cannot, under such conditions, ride from the recesses 25 in the flange 22 or up the inclined surfaces 23. When the rack is moved to its outer position, however, it is desirable that the rack be substantially free to rotative movement, and to this end the lock lever 29 has an extended lower portion 34 provided with a cam end 35, Fig. 3, adapted to contact with a pin 36 secured near the bottom of the case or cabinet, the construction being such that as the rack is moved to its outer position the cam portion 35 will engage the pin 36 and turn the lock lever 29 into substantially the dotted line position partially indicated by Fig. 3, thereby freeing the rack to rotative movement. When the rack is thus free to rotative movement and has been turned partially around so that the rack will injure the case or cabinet if then moved toward its inner position, it is equally desirable that such inward movement of the rack be prevented, and to this end the arm 34 of the lock lever 29 has a recessed portion 37, Fig. 3 which, when the lock lever has been disengaged from the shaft or upright 9 by engagement of its cam portion 35 with the pin 36, is seated upon or about a pin 38. On partial rotation of the rack at such time, even if the rack be slightly moved inward, the hook end 28 of the lock lever 29 will be prevented from moving inward by engagement with the unrecessed portion 39 on the lower part of the shaft or upright 9, the construction being such that the rack cannot at such time be moved bodily toward its inner position. Let it be assumed that the rack has been moved to its outer position and that the pin 36 acting upon the cam portion 35 of the lock lever has disengaged the hook end 28 from the recess 27. At such time the lock lever assumes the position indicated by dotted line, Fig. 3, and the rack is free to be rotated. If at such time, it be partially rotated and then released, it will, through the gravity inclines 23 and coacting 130

parts, be automatically turned into the desired predetermined position such that the rack will not injure the case if moved thereto. If, on the other hand, attempt be made 5 to push the rack bodily into the case, when it has been partially turned from such predetermined position, the hook end 28 of the lock lever 29 which then engages the blank or unrecessed portion 37 at the lower end of the shaft or upright 9, will prevent such 10 bodily movement of the rack into the case by engagement of its recessed portion 37 with the pin 38. When the rack is turned in order to display the goods on all sides thereof, the rollers 21 ride upward on the inclines 23 and the shaft or upright 9 likewise rises, the parts taking the position partially indicated by dotted lines in Fig. 3, and when the 15 rack is turned automatically into the desired predetermined position, the parts assume the relation indicated by full lines in Fig. 3, at which time the hook portion 28 of the lock lever 29 is so positioned with respect to one of the recesses 27 as to be movable into locking 20 engagement therewith upon movement of the rack toward its inner position.

It will be noted that where the inclines 23 at each side portion of the flange 22 meet, as at points 24, they present a sharp edge 25 or ridge at 24 on which the rollers 21 will not readily stand, so that should the rack be rotated when in its outer position to bring the rollers 21 substantially above the portions 24, the rollers will automatically ride to one 30 side or the other of these portions 24 upon slight disturbance of the rack to automatically position the rack in predetermined relation with the case.

Obviously various changes may be made 40 in the details of the mechanism described within the true scope of the present invention, and the different features of the invention as defined by the claims may be used either conjointly in the same display device, 45 or separately. For instance, the automatic self righting feature, which causes the rack to automatically assume its predetermined position with the rack bars parallel to the case when the rack is turned from said position and released, may be employed in a display device without the locking and unlocking features.

What is claimed is:—

1. The combination with a cabinet and a 55 revoluble rack movable into and out of the cabinet, of means for automatically righting the rack into a predetermined position relatively to the cabinet when rotated a partial revolution and released.

60 2. The combination with a cabinet and a revoluble rack movable into and out of the cabinet, of means permitting rotation of the rack in its outer position and also acting, when the rack is rotated from parallel relation with the cabinet and released, to auto-

matically adjust it into its normal or parallel position relatively to the cabinet.

3. The combination with a goods display rack, a reciprocating carriage and a revolvable standard mounted thereon and supporting the rack and gravity means for automatically righting the rack into a predetermined position relatively to the cabinet when rotated a partial revolution in its outward position and released. 75

4. In a display device the combination of a case or cabinet, a rack movable to and from a position within the cabinet, said rack being freely rotatable when in its outer position and gravity means for automatically rotating the rack into a predetermined position with respect to the case or cabinet when the rack is partially rotated and released. 80

5. In a display device, the combination of a case or cabinet, a carriage movable to and from a position within the case or cabinet, a flange mounted on the carriage and having its upper surfaces reversely inclined toward each side thereof, a revolvable rack mounted on the carriage and adapted to be rotated 85 when the carriage is in its outer position, supporting devices for engaging the rack and adapted to travel upon the inclined surfaces of the flange and acting automatically to rotate the rack into a predetermined position with relation to the case or cabinet when the rack is partially rotated in its outer position and released. 90

6. In a display device the combination of a case or cabinet, a revolvable rack movable 100 to and from a position within the cabinet, means for automatically righting the rack into a predetermined position relatively to the cabinet when rotated a partial revolution in its outer position and means for locking 105 the rack in said predetermined position when the rack is moved inward of the case or cabinet.

7. In a display device, the combination of a case or cabinet, a carriage movable to and from a position within the case or cabinet and having a standard rising therefrom, a flange surmounting said standard and having inclined upper edges extending from the front and rear of said flange in a downward 110 direction toward the sides thereof, and rotatable rack mounted for rotative movement in said standard and having supporting projections adapted to ride upon the inclined surfaces of the flange to automatically right 115 the rack into a predetermined position relatively to the case or cabinet when it is rotated a partial revolution in its outer position and released.

8. In a display device, the combination of a case or cabinet, a carriage movable to and from a position within the case or cabinet, a rotatable rack mounted on said carriage, means between the carriage and rack for causing the latter to move vertically when 120 125 130

- rotated from a predetermined position with relation to the case and acting automatically to return the rack to said predetermined position when rotated a partial revolution at the front of the case or cabinet and released.
9. In a display device, the combination of a case or cabinet, a carriage movable to and from a position within the case or cabinet, a rotatable rack mounted on said carriage, means between the carriage and rack for causing the latter to move vertically when rotated from a predetermined position with relation to the case, acting automatically to return the rack to said predetermined position when rotated a partial revolution at the front of the case or cabinet and means to prevent such vertical movement of the rack when it is being moved to and from its position within the case or cabinet.
10. In a display device, the combination of a case or cabinet, a rotatable rack movable to and from a position within said case or cabinet, and means for automatically righting the rack into a predetermined position when partially rotated from said position and released, said means comprising a cam member and a device acting against said cam member.
11. In a display device, the combination of a case or cabinet, a rotatable rack movable to and from a position within said case or cabinet, and means for automatically righting the rack into position parallel with the case when partially turned from such position and released, said means comprising a cam member and a device acting against said cam member, one of said parts being connected to rotate with the rack and the other being non-rotatable with the rack.
12. In a goods display apparatus, the combination with a standard and a goods display rack rotatable freely in a horizontal plane and supported on the standard, of a

cam member on one of said parts having semicircular cam surfaces, and bearing members on the other of said parts and co-operating with said surfaces to automatically restore the rack to its normal position when it has been revolved out of such position and released.

13. The combination with a display cabinet, a carriage guided to move transversely in the bottom thereof and a stop for limiting its outward movement, of a display rack mounted on the carriage and revolvable in a horizontal plane, coöperating cam and bearing members arranged one on the carriage and the other on the rack and serving to cause the rack to automatically turn into a predetermined position in respect to the cabinet, and coöperating to permit the rack to be rotated only upon the application of a force greater than that required to cause the carriage to traverse its guide.

14. In a display device, the combination of a case or cabinet, a rack movable to and from a position within the case or cabinet and horizontally rotatable when in front position, means for automatically righting the rack into parallel relation with the case or cabinet when said rack is partially rotated in front position and released, said means including a cam and a bearing member moved by said cam as the rack is rotated, and means acting upon the bearing member to prevent movement of the bearing member by said cam when the rack is being moved toward its inner position.

In testimony whereof, I have signed my name to this specification, in the presence of two subscribing witnesses.

ANTHONY VANDERVELD.
